[57] **CLAIM**

The ornamental design for a thermoelectric table for keeping food hot or cold, as shown and described.

DESCRIPTION

FIG. 1 is a front and left side perspective view of a thermoelectric table for keeping food hot or cold showing my new design;

FIG. 2 is a rear and right side perspective view thereof;

FIG. 3 is a front and left side perspective view of a thermoelectric table for keeping food hot or cold showing a second embodiment of my new design;

FIG. 4 is a rear and right side perspective view of FIG. 3; FIG. 5 is a front and top perspective view of a third embodiment of the thermoelectric table for keeping food hot or cold; and,

FIG. 6 is a rear perspective view of FIG. 5.

The broken line showing of a heating and cooling element in FIGS. 2, 4 and 6 is for illustrative purposes only and forms no part of the claimed design.
